UNITED STATES PATENT OFFICE.

WILLIAM A. DOUGLAS, OF CENTRALIA, WASHINGTON.

LIFE-SAVING SUIT.

1,068,866.

Specification of Letters Patent.

Patented July 29, 1913.

Application filed December 7, 1912. Serial No. 735,471.

To all whom it may concern:

Be it known that I, WILLIAM A. DOUGLAS, a citizen of the United States, residing at Centralia, in the county of Lewis and State 5 of Washington, have invented new and useful Improvements in Life-Saving Suits, of which the following is a specification.

My present invention pertains to life saving suits; and it contemplates the provision 10 of a suit constructed in such manner that it can be expeditiously and easily put on over ordinary clothing, and one calculated to maintain a person in upright position in the water with the upper portion of the body 15 clear of the water, and also calculated to effectually exclude water from the clothing and body of the wearer so as to prevent the wearer from suffering from cold while in the water.

20 Other advantageous characteristics of the invention will be fully understood from the following description and claim when the same are read in connection with the drawings, accompanying and forming part of 25 this specification, in which:

Figure 1 is a broken front elevation of the suit constituting the best practical embodiment of my invention of which I am cognizant. Fig. 2 is a detail vertical section 30 taken through the upper portion of the suit and the flaps thereof in a plane at one side of hood.

Similar numerals of reference designate 35 corresponding parts in all of the views of the drawings.

Among other features my novel life saving suit comprises trousers legs 1 which are closed at their lower ends and are there provided with foot-receiving portions 2 having 40 soles 3. The trousers legs and their foot portions may be formed of any water-proof material compatible with the purpose of my invention without involving departure from the scope of the same as claimed. At its 45 upper end the trousers portion of the suit is joined in water tight manner to or is integral with the body portion 4 which is also formed of suitable water-proof material, and the said body portion 4 is surrounded by 50 and carries an annular inflatable receptacle 5, which in common with the trousers portion 1 and the body portion 4 is formed of water-proof material. It will also be noticed at this point that the receptacle or belt 5 55 when inflated and distended is tapered or

gradually reduced in size downwardly, this with a view to enabling the belt to better maintain the wearer of the suit in an upright position in the water.

Connected to the air receptacle or belt 5 60 and preferably in a detachable manner is an inflating device 6, which *per se* may be of any description, though I prefer that it be of bellows type as illustrated.

The body portion 4 of the suit is, in turn, 65 joined in water tight manner to the upper portion 7 of the suit which together with all of its appurtenances is formed of a water-proof material thinner and more pliable than that of which the remainder of the 70 suit is made. The said upper portion 7 is provided with arms 8 that terminate in closed finger portions 9; and it is also provided with a neck opening 10, a hood 11 on which are strings 12, and flaps 13. These 75 flaps when the suit is put on are secured in closed position overlapping the upper portion 7, by tabs 14 which are connected to the flaps in permanent manner, and are designed to be engaged with buttons 15 on the upper 80 portion 7. I would have it understood, however, at this point that any means other than the tabs 14 and the buttons 15 may be employed to secure the flaps 13 in closed position, without involving departure from the 85 scope of my claimed invention.

The back portion of the hood 11 is carried by the common back portion 13^x of the flaps 13 while the front and side portions of the hood are loose, and when the hood is 90 untied and the flaps 13 are unfastened or disconnected from the front of the upper portion 7, the upper end of the suit is opened from shoulder to shoulder. This is materially advantageous inasmuch as it adapts the 95 suit to be quickly and easily put on as is necessary in cases of disaster at sea.

After the suit has been donned, the wearer has but to close and lap the flaps 13 one over the other and over the upper portion 7, and fasten the flaps and inflate the receptacle or belt 5 when the wearer is ready to go into the water without discomfort; the suit serving to effectually exclude the water from the clothing and person of the wearer so that 100 the immersion of the wearer is not attended by discomfort.

The hood may be used or not in the discretion of the person using the suit, but when it is employed it is simply necessary 110

to draw it over the head and secure it in such position through the medium of the strings 12.

The inflating device 6 is preferably made 5 detachable, as before stated, in order that it may be readily repaired when occasion demands.

When deemed necessary or desirable, the suit may be provided with shoulder straps or 10 suspenders 14^x, connected at their ends to the body portion of the suit. See dotted lines in Fig. 1 and full lines in Fig. 2.

When the suit is not in use it may be folded into a compact bundle which will take 15 up but little space on shipboard.

Having described my invention, what I claim and desire to secure by Letters-Patent, is:

A life saving suit having leg portions, a 20 body portion and an upper portion formed

of water-proof material and also having an inflatable receptacle surrounding the body portion and reduced in size downward and equipped with an inflating device; the upper portion being provided with arms, and being also provided with a hood, and flaps constructed to be lapped one over the other and over the upper portion, and means for detachably connecting the flaps to the upper portion, the flaps extending from shoulder 25 to shoulder of the suit, whereby when the flaps are unfastened the entire upper end of the suit is opened, for the purpose set forth.

In testimony whereof I have hereunto set my hand in presence of two subscribing witnesses.

WILLIAM A. DOUGLAS.
